UNITED STATES PATENT OFFICE.

SAMUEL D. WEBB, OF WASHINGTON, DISTRICT OF COLUMBIA, ASSIGNOR OF
ONE-HALF TO WILLIAM B. REILLY, OF SAME PLACE.

DESIGN FOR A SASH-HOLDER.

SPECIFICATION forming part of Design No. 34,347, dated April 9, 1901.

Application filed March 13, 1901. Serial No. 51,026. Term of patent 14 years.

To all whom it may concern:

Be it known that I, SAMUEL D. WEBB, a citizen of the United States, residing at Washington, in the District of Columbia, have invented and produced a new and original Design for Sash-Holders; and I do hereby declare the following to be a full, clear, and exact description of the same, reference being had to the accompanying drawings, forming a part thereof, and in which—

Figure 1 is a plan view of a sash-holder, showing my new design, Fig. 2 an edge view of the same, and Fig. 3 a section taken on the line *x x* of Fig. 1, these three views being deemed necessary to fully illustrate my design.

As shown in the said drawings, the leading or material feature of my design consists of the fan-shaped disk A, having a centrally-
20 raised portion B, tapering from its lower part

to the enlarged V-shaped portion C, which projects slightly into the central opening D, said opening extending through the said sash-holder. The semicircular edge of said sash-holder is of a tapering shape and is provided with sharp-edged serrations E E, extending in opposite directions to each other on each side, as shown, while the opposite tapering end F is provided with a small circular opening G.

Having thus described my new and original design, what I claim is—

The design for a sash-holder as herein shown and described.

In testimony whereof I affix my signature 35
in presence of two witnesses.

SAMUEL D. WEBB.
